PORTABLE BARBECUE

Maurice B. Pollard, Pampa, Tex.

Application August 4, 1950, Serial No. 11,610

Term of patent 14 years

(Cl. D81—10)

To all whom it may concern:

Be it known that I, Maurice B. Pollard, a citizen of the United States, residing at Pampa, in the State of Texas, have invented a new, original, and ornamental Design for a Portable Barbecue, of which the following is a specification, reference being had to the accompanying drawing, forming part thereof.

Fig. 1 is a perspective view of a portable barbecue showing my new design in open position; and Fig. 2 is a side elevational view thereof.

The other end and the other side, not shown, are the same as the respective end and side shown except for the omission of the door panel and the front ledge.

I claim:

The ornamental design for a portable barbecue, as shown and described.

MAURICE B. POLLARD.
